[57] CLAIM

The ornamental design for a wall plate, as shown and described.

DESCRIPTION

FIG. 1 is a perspective view of a wall plate for a switch illustrating my new design;

FIG. 2 is a front elevational view of the wall plate of FIG. 1.

FIG. 3 is a rear elevational view of the wall plate of FIG. 1.

FIG. 4 is an end plan view of the wall plate of FIG. 1.

FIG. 5 is a side elevational view of the wall plate as in FIG. 1.

FIG. 6 is a horizontal sectional view of the wall plate of FIG. 2 taken along the line 6—6 of FIG. 2.

FIG. 7 is a vertical sectional view of the wall plate of FIG. 2 taken along the line 7—7 of FIG. 2.

FIG. 8 is a horizontal sectional view of the wall plate of FIG. 2 taken along line 8—8 of FIG. 2.

FIG. 9 is an elevational view of a wall plate for a wall receptacle showing a second embodiment of my design.

FIG. 10 is an elevational view of a wall plate for two side-by-side switches showing a third embodiment of my design.
